UNITED STATES PATENT OFFICE.

EDWARD BIGNELL, OF LINCOLN, NEBRASKA, ASSIGNOR TO CONCRETE PILING CO., OF SEWARD, NEBRASKA, A CORPORATION OF NEBRASKA.

PILE.

Application filed June 20, 1924. Serial No. 721,221.

This invention relates to piling such as is contemplated by my prior Patent #1,241,813, dated October 2, 1917. In that patent certain provision was made for the utilization of 5 jets of water at the nose of the pile and at the surface or surfaces of the pile to displace earth in advance of the piling and to lift it to the top of the excavation and at the same time to lubricate the side of the pile so that 10 it will quickly sink.

In the illustrated embodiment of the invention disclosed in my prior patent of October 2, 1917, a hollow piling was shown with pipes extending longitudinally thereof 15 and jet nozzles imbedded therein. While the invention therein disclosed admirably served the purposes for which it was intended, I have found that a less expensive pile can be constructed and substantially 20 the same results may be obtained by a removable jetting device which may be temporarily attached to the pile for the purpose of hydraulically sinking it into the earth and which may be easily removed after the pile 25 has been sunk to the required depths so the jetting device can be utilized in connection with another pile.

According to my present invention, not only can the pile be made much less expensively but the necessity for leaving the jetting means imbedded in the ground is entirely eliminated, so it is obvious that there 30 will be a considerable saving where a number of piles are sunk.

The novelty of my invention will be apparent by reference to the following description in connection with the accompanying drawings, in which—

Fig. 1 is a perspective view of a pile constructed in accordance with my invention, showing the jetting device applied.

Fig. 2 is a vertical longitudinal sectional view through the pile, the jetting device being shown partly in section and partly in 45 elevation.

Fig. 3 is a cross sectional view through the upper portion of the pile and through the tong receiving socket, and

Fig. 4 is an enlarged detail view of one of 50 the jaws of the tongs.

The pile 1 may be constructed of suitable material such as cement, concrete or the like and it is preferably rectangular in cross section. At the upper end of the pile is a jaw 55 receiving socket which may consist of a pipe

2 anchored to the body portion of the pile by anchor wires 3 imbedded in the concrete and having anchoring ends 4 and 5. A center guide pin 6 is imbedded in the upper end of the pile. At the nose of the pile is a central orifice or opening 7 merging off to the side of the pile at 8 to receive one tube 9 of a jetting device so that water can be forced into the channel consisting of 7 and 8 to displace earth in advance of the pile as will 60 be hereinafter apparent.

The jetting device is shown as including a rectangular manifold or tubular ring 10 supplied with water from a tube 11, connected to any suitable source of supply. On 70 three sides of the manifold are jetting tubes 12, the fourth side supplying the tube 9, all of the tubes having upwardly and outwardly disposed jetting nozzles 13 which causes water under pressure to flow along the sides 75 of the pile and since the water is directed upwardly, it will be apparent that the earth which has been displaced by the water issuing from the nozzle or opening 14 in the channel 7 will be elevated by the jetted water 80 passing from the jets 13, the water also serving to lubricate the pile so that it may be allowed to sink by gravity.

The tubular members 12 and the member 9 are connected to the manifold by flexible 85 connections 15, all substantially alike and the tubular members 12 rest upon seats or projections 16 while the member 9 seats in the open end of the tube 8. The lower ends of the members 12 are preferably closed while 90 the lower end of the member 9 is open to communicate with the channel 8 and the tubular portion 7. Means is provided for lowering the pile into position so that the jetting device may become effective in sinking 95 the pile. The lowering device should be such that it can be detached from the pile after the pile is sunk and it should also be constructed that its withdrawal will be effective in causing the withdrawal of the jetting device, so I have shown the hereinafter 100 described mechanism for accomplishing this result.

The lowering device consists of a tongs comprising two jaws 17 and 18 pivoted together at 19 and having co-operating lever ends 20 and 21 connected by the chains 22 and 23, with a pull cable 24 so that upon an upward pull of the cable 24 the jaw members 17 and 18 would tend to hold the pins 110

or lugs 25 and 26 into engagement with the socket member or tube 2. The tongs however are also held in engagement with the tubular member 2 by a retaining bar 27 which is guided in its vertical movement on the pin 6 and which has two slots 28 and 29 through which the upper portions of the jaws 17 and 18 project, there preferably being rollers 30 and 31 so that the bar can ride on the inner curved faces of the jaw members 17 and 18 to force the jaws 17 and 18 apart when the bar 27 is raised by the sling 32 connected to the cable 33 accessible from the top of the ground.

15 It will be apparent by reference to Fig. 2 that so long as the retaining or locking bar 27 is in normal position resting upon the top of the pile and held against lateral movement by the pins 6, the lugs 25 and 26 20 will hold in the socket 2 but when the bar 27 is raised, to spread the jaws 17 and 18 apart, they must release and since they are connected to the manifold 10, the jetting device will be pulled from the well or excavation made by sinking the pile when the 25 elevating jaws or tongs are pulled out. The manifold 10 is connected to the two jaws by the side rods 34 and 35 fastened to the jaw members by the chains 36 and 37, the 30 ends of the rods 34 and 35 being received in the sockets or recesses 38 and 39 so that the manifold will be held in its proper position during the jetting, the flexible connection permitting the movement of the jaws to releasing position without disturbing the rods 34 and 35, as obviously these rods could 35 not be moved away from the side of the pile without breaking connection with the manifold, therefore the engaging ends of the 40 jaws 17 and 18 will have free movement independent of the bars or rods 34 and 35.

It will be apparent however, that just as soon as the pull is exerted by the tongs, the entire jetting frame can be released from 45 the pile and the pile will be submerged or partially submerged in the earth. Attention

is particularly directed to the fact that all of the advantages accruing from the construction shown in my Patent #1,241,813 can be had with the present invention without the necessity of making the pile hollow or imbedding the central water supplying orifices or channel members therein, therefore the cost of sinking the piles and the cost of the piles themselves will be reduced 55 as compared with the specific arrangement shown in my Patent #1,241,813. In other words, I accomplish all that can be accomplished by my former patent by a much less expensive means and a by no means less 60 important feature is the device for lowering the pile and for raising the jetting devices.

What I claim and desire to secure by Letters-Patent is:

1. In combination with a pile having a 65 nozzle at its nose and a transverse socket at its upper end, tongs having jaws for engaging the socket, a jetting frame carried by the tongs and surrounding the pile, the jetting frame having communication with 70 the nozzle, means for supplying water through the frame of the nozzle to remove material in advance of and around the pile and means for releasing the tongs from the pile so that the tongs can be withdrawn and 75 remove the jetting frame.

2. In combination with a pile structure, a submerging apparatus comprising jetting pipes arranged about the structure, hanger jaws attached to the frame and detachably 80 connected with the pile structure, a lowering cable having closing connection with the jaws, whereby the pile structure and submerging apparatus are lowered in assembled relation, and a lifting cable having opening 85 connection with the jaws, whereby the jaws are detached from the pile structure and the jaws and submerging apparatus removed from the pile structure.

In testimony whereof I affix my signature.

EDWARD BIGNELL.
